UNITED STATES PATENT OFFICE

2,329,390

FIRE EXTINGUISHING NOZZLE

Thompson W. Burnam, Inglewood, Calif.

Application July 7, 1941, Serial No. 401,315

5 Claims. (Cl. 169—39)

The present invention relates to automatic spray heads of the type that are placed in structures that entail fire hazard and are intended to be automatically opened by the heat of the fire.

There are at present many installations of automatic spray heads including fusible links intended to be released by the heat of the fire. These conventional spray heads form a spray of water by directing the water leaving the head against a star-shaped target. It has been established that such conventional spray heads depend for their operation upon such a large quantity of water that fire engineers estimate that about 70% of the total fire damage in fires where such conventional heads have been used have been due to the water released from such heads.

Fire extinguishing nozzles operating upon the impingement system, and of the type described, for example, in Patent No. 2,235,258 to William Walter Jones, issued March 18, 1941, and described in the pending application of Raymond W. Larter, Serial No. 379,178, filed on February 17, 1941, are effective for extinguishing fires although using but a relatively small quantity of water.

It is the object of the present invention to provide a fire extinguishing nozzle of the impinging jet type with a means including a fusible link by which such impinging jet form of nozzle may be automatically released by the heat of the fire. It is a further part of the principal object of the present invention to provide a structure which may be produced by a simple modification of installations previously equipped with conventional sprinkler heads making use of the automatic release means of such sprinkler heads (including their fusible links) for the purpose of operating the nozzle or nozzles operating on the impinging jet principle.

By means of the present invention, a device is provided which may be interposed between the water supply system and the conventional sprinkler head for forming a water spray by the impinging jet principle and connected to the fusible elements of the conventional spray head in such manner that such fusible elements may be made to control the release of water through the impinging jet nozzle without permitting the flow of water through the conventional sprinkler head.

The device of the present invention, together with various objects and advantages thereof, will best be understood from a description of a preferred form or example of a device embodying the

invention. For this purpose, I have hereinafter described a preferred form of the invention in connection with the accompanying drawing, in which

Figure 1 is an elevation mainly in vertical section of one form of the device.

Figure 2 is an elevation mainly in a vertical section of a modified form of device.

Referring to the drawing, I generally indicate a water supply line having a coupling 2. In normal installations, the socket of the coupling 2 is screw-threaded to a conventional sprinkler head 3, which consists of a nipple 4 having the outlet 5 and the curved arms 6 supporting a star-shaped target 7 in position to break up into a spray the water discharged from the outlet 5. For closing such outlet until released by the heat of the fire, such conventional sprinkler head is provided with a cap 8 contacting a bar 9, which in turn contacts a substantially horizontal bar 10 which engages a pin 11 held by the arms 6. A diagonal fusible link 12 is provided between the bars 9 and 10 and is so arranged that upon fusing of the link 12 the cap 8 will be released to be forced off the outlet by the pressure behind the water supply mains to the device.

For the purpose of the present invention, I bodily retain such conventional sprinkler head but disconnect the same from the coupling 2 and interpose a nozzle 14 of the type intended to form a water spray by the impinging jet principle. The nozzle 14 consists of two members 15 and 16, the lower member 16 having a threaded portion 17 for engagement with the coupling 2 and preferably supporting a screen 18 for the purpose of screening the water supplied to the nozzle and to prevent scale or foreign particles from clogging the orifices of the device. The lower member 16 is indicated as provided with an enlargement 19 forming a water chamber back of the plurality of pairs of orifices 20. The orifices 20 are formed in a V-shaped groove 21 of the body, each pair of orifices being arranged to form impinging jets of water, which impinging jets upon striking each other will subdivide the water into the form of a spray of uniform droplets of water. The design of the water chamber, the orifice diameters and angles of the orifices are preferably made to accord with the disclosure of the aforementioned patent to Jones. The body is preferably provided with a plurality of such pairs of orifices spaced uniformly apart circumferentially, and the spacings of the pairs of orifices are practically in accordance with the disclosure of the aforementioned Larter application

in order that the spray of water formed by each adjacent pair of orifices will be properly combined to form a single spray pattern from the nozzle. I have also indicated additional pairs of impinging jets 22, which may be formed below the enlargement, and other pairs of impinging jets 23, which may be formed above the enlargement.

The upper member 15 of the nozzle provides a socket 24 into which the end of the conventional sprinkler head is threaded. This member also has an opening 25 through which the operating stem of the automatic release means may pass.

For closing the orifices of the nozzle 14 I provide a gasket 26 seated against a shoulder 27 of the inlet to the member 16, the gasket 26 thus serving as a valve head. This gasket 26 is engaged by a valve stem 28, which is preferably reduced at its end, as indicated at 29, to permit the valve head to have a rocking action relative to the valve stem. The valve stem extends through the opening of the upper member 15 and contacts the cap 8 of the conventional sprinkler head, so that as long as the cap 8 is retained against the outlet by the fusible link structure the stem 28 will firmly hold the gasket or valve head 26 against the inlet and thereby exclude passage of water through the orifices of the nozzle 14. In order to insure the proper operation of the device, I provide a relatively loose fit between the stem 28 and the member 15 of the nozzle, and I reduce the diameter of the stem 28, as indicated at 30. Within the socket of the upper member 15, I provide a gasket F, or a second valve head, having an opening 31 therethrough of a size of the reduced diameter of the stem, which gasket is, therefore, adapted to be engaged by the shoulder of the stem and forced against the inlet to the conventional sprinkler head, upon release of the cap 8, to thereby inhibit the passage of the water through the outlet of the conventional head, forcing and directing all of the water discharged out of the impinging orifices of the nozzle 14.

Now, referring more particularly to Figure 2 of the drawing, I have shown a somewhat modified method of adding the impinging type of nozzle 14 to spray installations having the conventional head, and in the figure I have indicated the parts in a similar manner to those employed in Figure 1 and by similar reference characters.

In Figure 2 I employ a T coupling 31 between the water supply line 1 and the conventional sprinkler head 3. The valve head 32 is shown held against the outlet of the pipe 1 by the stem 33 which engages the cap 8 of the conventional sprinkler head to be released by operation of the fusible link 12 thereof. A further valve head 34, in this case mounted directly above the valve head 32, is provided for closing against the inlet of the conventional sprinkler head on operation of the fusible link so as to shut off the supply of water through the conventional head.

To the stem of the T coupling 31 is connected a nipple 35, preferably including a screen 36 leading to the impingement jet nozzle 14, which in this case is shown as positioned in a depending position. The socket of the member 15 of the nozzle 14 is indicated as closed by a plug 37. While I have shown a single impinging jet nozzle connected to the stem of the T-shaped coupling, it is obvious that suitable pipe connections may be made to any number of impinging jet nozzles so as to allow a plurality of such nozzles, if de-

sired, to be operated by a single fusible link means. It is also obvious that the impinging jet nozzle 14 may be mounted in any position, upright or horizontal as the particular hazard conditions dictate.

While the particular forms of the invention herein described are well adapted to carry out the objects of the present invention, it is to be understood that various modifications and changes may be made, and this invention includes all such modifications and changes as come within the scope of the appended claims.

I claim:

1. In a device of the class described, a nozzle member having a plurality of orifices in its walls arranged in pairs to form impinging jets, means for connecting said member to a water supply system, a valve including a valve head within said member for controlling the water supply to said member, a stem extending through said member and contacting said valve head for retaining the same closed, said stem extending exterior of the member and provided with a second valve head to be closed by the movement of said stem for releasing the first valve head, and a fusible link means for controlling the release of said stem.

2. In a device of the class described, a nozzle for providing a water chamber from which a plurality of pairs of orifices lead, said orifices being arranged to form impinging jets, said nozzle including a body member and a socket member, means for attaching said body member to a water supply system, a valve head for said body member, a stem contacting said valve head and loosely passing through an opening in said socket member, means forming a closure for said socket member and provided with a fusible link for controlling the release of said stem, a head within said socket member and movable upon the release of said stem for closing the outlet from said socket member.

3. A fire extinguishing nozzle, comprising a nozzle body having in its walls a plurality of pairs of orifices arranged to form impinging jets, said nozzle having an inlet adapted for attachment to a water supply system, a valve head within said body adapted to close said inlet, a stem passing through said body normally contacting said head for holding the same in the closed position, said stem passing loosely through said body, a valve seat attached to said body through which said stem extends, a second valve head on said stem and above said orifices adapted to be moved to closing position by the movement of said stem for opening the first valve head, and a fusible link means for controlling the movement of said stem.

4. In a device of the class described, a combination with a sprinkler head having a fusible link, a nozzle having a plurality of pairs of orifices in its walls arranged to form impinging jets, means for attaching the said nozzle to said sprinkler head, means for attaching the said nozzle to a water supply line, said latter means including a valve seat, a valve head for normally contacting said valve seat, a stem contacting said valve head and the fusible link means of said sprinkler head for normally retaining said valve head in the closed position, said first-mentioned means including a valve seat, and a second valve head associated with said stem for contacting said second-mentioned valve seat and closing the inlet of said sprinkler head upon release of said fusible link means.

5. In a device of the class described, a sprinkler head having an outlet, a valve for closing the said outlet, a fusible link means normally maintaining the said valve closed, a water supply means, a nozzle interposed between the said sprinkler head and water supply means and provided with a plurality of pairs of orifices for forming impinging jets, a valve head for closing the inlet to said

nozzle, a second valve head for closing the inlet to the said sprinkler head, a stem upon which both the said valve heads are secured extending from the said nozzle inlet valve head to the said sprinkler outlet valve so that upon operation of the said fusible link means to open the nozzle inlet valve the sprinkler inlet valve is closed.

THOMPSON W. BURNAM.
